GRAPHIC CHART

Filed Feb. 14, 1928

UNITED STATES PATENT OFFICE

EDWARD M. ANDRES, OF MARBLE, COLORADO, ASSIGNOR OF ONE-HALF TO RUSSEL W. TALLMAN, OF GUNNISON, COLORADO

GRAPHIC CHART

Application filed February 14, 1928. Serial No. 254,271.

This invention relates to graphic charts of the type shown and described in my application for Patent No. 210,084 filed August 2, 1927, patented May 21, 1929, number 1,713,811, of which the present application is a continuation.

The chart disclosed in the original application comprises a face member and a back member fastened one upon the other. The 10 face of the back member is colored distinctively with respect to the surface of the face member so that when parts of the face member are removed the exposed portions of the back member will stand out in contrasting 15 prominence.

The face member has removable strips formed between perforated or otherwise weakened lines and spaces are provided at the ends of these strips or at the ends of the 20 divisions on the face member in which the strips are formed, for insertion of the names of subjects, individuals, teams, shifts and the like.

The face member is graduated and in the 25 use of the chart, the strips are torn away to designate degrees of progress by the exposed portions of the contrasting face of the background.

It has been stated in the first application 30 that the two members are fastened together, exclusive of the strips of the face member, by means of a suitable adhesive and it is an object of the present invention to provide different fastening means that have been 35 found to be particularly suited for the purpose.

The fastening means referred to are of a solid character and mechanically applied, sewing, stitching or stapling by means of 40 thread or wire being preferred.

Another object of the invention is to provide in a chart of the above described type, removable and renewable means for inserting the names of subjects or persons opposite 45 to the divisions in which the grade-indicating strips are formed.

A further object is to provide the scales and grade indicia in the form of vertical columns that they may be shaped to resemble 50 a thermometer, and still other objects reside

in details of construction and novel arrangements of parts as will be brought out in the course of the following description.

In the accompanying drawings in which like characters of reference designate corresponding parts throughout the views,

Figure 1 represents a face view of the improved chart;

Figure 2, an enlarged fragmentary section on the line 2—2 Figure 1;

Figure 3, an enlarged fragmentary section taken on the line 3—3, Figure 1;

Figure 4, a similar section along the line 4—4, Figure 1;

Figure 5, a fragmentary face view of the chart showing a modified method of fastening the sheet-members of the chart together;

Figure 6, an enlarged section on the line 6—6, Figure 5; and

Figure 7, a fragmentary face view of a chart of modified form.

In the drawings, the reference numeral 5 designates the back member of the chart and 6 the face member of the same. Both members are preferably made of paper, and the 75 back member is usually heavier than the other to give the required rigidity to the chart.

The upper surface of the back member is of a distinctive color contrasting with the 80 color of the face member, as clearly indicated in the drawings as at 7.

The two sheets of paper as shown in Figure 1, are fastened together by sewing or stitching in a manner hereinafter to be more 85 fully described.

The face member is graduated by horizontal lines 8 and vertical lines 9, the vertical ruling being divided into columns by heavier lines 10. Between each two horizontal lines 90 is a removable strip 12 defined by two parallel perforated or otherwise weakened lines and the chart has an alinement with these strips oblong windows 13 for the insertion of the names of subjects, individuals, teams, shifts, or other matter, the progress or advance of which is to be indicated on the graduated scale.

The names are printed or typewritten on a strip of paper 14 which is fastened upon 100

the back of the lower sheet by a suitable adhesive or other means so that it is readily removed or replaced, it being understood that the names are properly spaced so that they will register with the windows as indicated in Figure 1.

Above the columns and cooperative therewith are tiers of cumulative alphabetical designations 15 which designate the values 10 of the different graduations. Inasmuch as the designations are not a part of the present invention and their use has been fully explained in the original application, no further description is necessary.

15 The sewing or stitching by which the two sheets are fastened together is preferably applied in lines 16 along the edges of the chart and in lines 17 coincident with the horizontal lines between the removable strips. The lines 20 of stitches may be made by means of an ordinary sewing machine or on a machine constructed especially for the purpose.

In the use of the chart, the strips 12 are torn away in accordance with the progress 25 made by the person or in the subject designated in the space at the end of the strip, the exposed portion of the face of the back member clearly indicating by its contrasting color, the degree of said progress, by co- 30 operation with the scale on the face member.

The stitchings by which the two sheets are fastened together permit of the ready removal of any part of the strips without tearing or disturbing other parts of the face 35 sheet.

The chart may be used for commercial records such as those of salesmen in an industrial concern, and for other purposes of similar nature, but it is particularly adapted for 40 school work to separately indicate the progress of a number of pupils in one subject or of one pupil in a number of different subjects. In the form illustrated in Figure 7 the detachable strips 18 are arranged vertically on 45 the sheet between parallel lines represented by lines of stitches 19, as before, the graduated scale is formed by equidistant cross stripes 20 between the lines, and degree indications 21 outside the same.

50 In order to render the chart more attractive and to impress the significance of the same more clearly upon the minds of the pupils and other interested persons, circular portions of the face sheet are cut away at the lower ends of the columns formed by the vertical lines, to expose the contrasting surface of the back member in the form of bulbs 22. It will be observed that the columns thus 55 formed, simulate thermometers of conventional construction and that the portions of the surface of the back member, exposed by the removal of parts of the detachable strips represent in connection with the circular exposed portions at the lower ends of the col-

umns, the rising mercury of the thermometers.

In Figures 5 and 6 has been illustrated the method of fastening the sheets of the chart together by means of staples 23 applied along the lines at opposite sides of the detachable strips or along the marginal lines of the chart. The staples may be spaced farther apart than the stitches of the lines of sewing and they may be applied by any of the 75 stapling machines at present in use.

It is to be understood that the staples are the full equivalent of the sewing and that both methods of fastening the sheets together have been included in the above description 80 and in the hereunto appended claims by the general terms "stitched," "stitching" or "stitches".

Having thus described my invention what I claim and desire to secure by Letters Pat- 85 ent is:

1. A chart composed of a back member and a face member fastened together, the face member having removable strips to expose corresponding portions of the surface of the back member, and the chart having windows aligned with the respective strips, and a member back of the chart, bearing names registering with the respective windows.

2. A chart comprising a back member and a face member fastened together by stitches in substantially parallel lines, the face member having weakened lines between said parallel lines whereby to provide detachable 100 strips.

3. A chart comprising a back member, a face member fastened to the back member and having weakened lines between the fastening means, the members being apertured to provide a window, and a sheet bearing indicia 105 disposed to be seen through the window.

4. A chart comprising a back member, and a face member fastened to the back member and having removable strips to expose the back member, the members having registering apertures conjointly providing windows related to the strips, and a sheet bearing indicia disposed to be seen through the window.

5. A chart comprising a back member and a face member stitched together in parallel 110 lines, the face member having weakened lines between the lines of stitching to provide removable strips.

6. A chart of the character described, comprising a top member having a graduated 115 face, and a back-member having a face contrasting with that of the top-member, the two members being stitched together with their said faces uppermost, and the top-member having a removable strip to expose the face of the back member, whereby to indicate degrees of progress by means of the graduations on the face of the top-member.

7. A chart of the character described, comprising a top-member having a graduated 120

face, and a back-member having a face colored in contrast with that of the top-member, the two members being stitched together with their said faces uppermost, and the top-member having a removable strip to expose the face of the back member, whereby to indicate degrees of progress by means of the graduations on the face of the top-member.

8. A chart of the character described, comprising a top-member having a graduated face, a back member having a face distinctive in appearance from that of the top-member, the two members being stitched together with their said faces uppermost, and the top-member having a portion removable by a tearing action to expose the face of the back member whereby to indicate degrees of progress by means of the graduations on the face of the top-member.

10 15 20 In testimony whereof I have affixed my signature.

EDWARD M. ANDRES.
